UNITED STATES PATENT OFFICE.

CHARLES J. OLSON, OF MUSKEGON, MICHIGAN.

FLUID-PRESSURE MOTOR.

1,138,969.

Specification of Letters Patent. Patented May 11, 1915.

Application filed January 25, 1913. Serial No. 744,182.

To all whom it may concern:

Be it known that I, CHARLES J. OLSON, citizen of the United States, residing at Muskegon, in the county of Muskegon and State of Michigan, have invented certain new and useful Improvements in Fluid-Pressure Motors, of which the following is a specification.

This invention relates to fluid pressure motors and more particularly to a motor of this type designed for use in driving chain saws of the hand type, or for operating various other small tools.

It is one aim of the invention to provide a compressed air motor which will be economical in its consumption of air and in which the air supply will be automatically controlled so that when the saw or other tool driven by the motor is not in actual contact with the work, a comparatively small volume of air will be admitted to the motor and this volume will be automatically increased as increased resistance is offered to the operation of the saw.

Another aim of the invention is to provide a motor so mounted and constructed that it will be adapted to drive an endless saw, emery-wheel, and various tools designed to be fitted into a chuck carried by the motor shaft.

For a full understanding of the invention reference is to be had to the following description and accompanying drawings, in which:

Figure 1 is a vertical front to rear sectional view through the motor embodying the present invention. Fig. 2 is a side elevation thereof. Fig. 3 is a top plan view. Fig. 4 is a vertical transverse sectional view in the line 4—4 of Fig. 3. Fig. 5 is a vertical section on the line 5—5 of Fig. 4. Fig. 6 is a detail perspective view of one of the pawls, shown in Fig. 5.

Corresponding and like parts are referred to in the following description and indicated in all the views of the accompanying drawings by the same reference characters.

As will presently appear, the structure embodying the present invention includes twin motors having a common shaft, which shaft carries, between the motors, a sprocket for driving the endless saw, heretofore referred to, and at one end is provided with a chuck and at its other end is arranged

for the support of a buffing wheel, or the like.

In the drawings, the shaft above referred to is indicated by the numeral 1, and the sprocket mentioned includes in its structure a body consisting of a collar 2 to the opposite faces of which are secured flanges 3, the parts being connected preferably by rivets. This collar is keyed, or otherwise secured upon the shaft 1 at a point substantially midway between the ends of the shaft and, as before mentioned is located between the two compressed air motors from which power is derived. The sprocket also includes in its structure an annular disk 4 which is fitted between annular plates 5 and secured thereto by rivets 6, the outer peripheries of the plates 5 being located beyond the peripheries of the disk 4, as clearly shown in Fig. 4 of the drawings. This portion of the sprocket is rotatably received between the flanges 3 of the body portion thereof and a number of bearing rollers 7 are arranged between the flanges 3 and between the outer periphery of the collar 2 and the inner peripheries of the disk 4 and plates 5. The periphery of the disk is formed with teeth 9 with which the links 8 of the chain saw are arranged to coöperate. Inasmuch as this saw and the support therefor form the subject-matter of my co-pending application for patent on pneumatically operated chain saws, filed May 28, 1912, Serial No. 700,264, the saw and its support will not be further described in this case, and it is to be understood that any desired type of saw may be employed.

As illustrated in Fig. 5 of the drawings, the peripheries of the flanges 3 are formed with notches 12 and pivoted as at 13 upon the outer face of each plate are pawls 14 which are arranged to engage in the notches in the flanges 3 whereby to connect the first and last described sections of the sprocket for rotation in unison. Thus when the shaft 1 is rotated in one direction, that section of the socket comprising the disk 4 and plates 5 will be correspondingly rotated. In order, however, that the pawls 14 may be held out of engagement in the respective notches 12, the outer face of each plate 5 is formed adjacent the pivot for each pawl with an indentation 15 in which is adapted to seat a laterally projecting lug 16 upon the adjacent

pawl. Each plate is further formed with a similar indentation 17 so located that when the adjacent pawl has its lug 16 engaging therein, the end of the pawl will be held 5 in the respective notch 12.

As before stated, two compressed air motors are arranged upon the power-shaft 1, one located at each side of the sprocket above described, and these motors are of 10 counter-part construction, and consequently a description of one will suffice for both. Each of the compressed air motors, above mentioned, includes a casing consisting of a substantially annular body 39 to the sides 15 of which are secured heads 40 and 41. These heads are formed axially with openings to which the shaft 1 is rotatably fitted and the head 41 of each casing is provided with a laterally projecting flange 42 which is secured by means of bolts, or similar fastening devices 43 to the inner end of the stock of the saw, the stock being indicated in general by the reference numeral 43^a. Each head 41 is formed with a rearwardly projecting flange 44 and the handle of the device, which also constitutes a support for the motors, and which is indicated by the reference numeral 45, is formed at its forward end with forwardly projecting flanges 25 46 to which the flanges 44 are secured by means of screws 47. The rotor of each motor includes a hub 48 which is keyed to the shaft 1 and each rotor further includes a rim 49 and a web 50. At intervals the web 50 is 30 thickened to equal the width of the rim 49, as indicated at 51 and at each of these thickened portions constitutes a head in which is arranged one of the pistons of the rotor. These pistons are indicated by the numeral 40 52 and are in the form of plates slidably fitted in suitably formed sockets 53 in the heads 51 which sockets open at the periphery of the rim 49. Each piston is provided with stems 54 which fit slidably in openings 45 in the inner ends of the heads 51 and a spring 55 is arranged upon each of the stems and serves to hold the related piston 52 in extended relation, or in other words with its outer end projecting beyond the periphery of the rim 49. The said edges of the piston blades 52 travel over the inner surface of the annular body 39 of the casing in which the rotor is mounted, and this member of the casing is provided interiorly with 55 abutments 56 located at diametrically opposite-points and more specifically at the upper and lower sides thereof. The said member of the casing is formed at its rear side with passageways 57 and 58 which 60 communicate with the interior of the casing in front and in rear of the upper and lower abutments, respectively. These passageways 57 and 58 communicate with the inner end of an inlet port 59 which is formed in the 65 handle 45. The web 50 is formed with open-

ings 60 at points between the piston blades 52, and each head of the casing is bulged as at 61 to form an exhaust by-pass, there being two such by-passes in each of the cylinder heads and the two being located at diametrically opposite points. An annular series of exhaust openings 62 is formed in each head 50 and it is through these openings that the exhaust air may escape, it having passed around the rim of the rotor by 70 way of the by-pass passages 61 and through the openings 60 in the web 50 of the rotor.

It will now be understood that when air under pressure is admitted into the passages 57 and 58 it will act upon the projecting pistons 52, thereby setting the respective rotor in motion. It will further be noted that the by-passes 61 are so located that as each piston reaches a position substantially corresponding to that occupied by the lower piston in Fig. 1 of the drawing, or a position diametrically opposite thereto, the air under pressure back of the piston will be allowed to rush over the edges of the rim of the rotor and, passing through the 80 openings 60 will escape by way of the openings 62. In this manner, the exhaust of air from the rotors is rendered practically noiseless, and it will be observed furthermore that there is no chance whatsoever of the 85 rotors stopping in such position that they will not be immediately set in motion upon the admission of air under pressure through the port 59.

The handle 45 is formed at the intake end 100 of the passage 59 with a recess 63 and with a nipple 64 to which is clamped or otherwise attached one end of a flexible tube 65 which serves to conduct air under pressure from any suitable source of supply to the 105 motors. The throttle valve which controls the supply of air under pressure through the passage 59 is indicated at 66 and is arranged to seat at the intake end of the said passage and the stem of this valve is indicated by the numeral 67 and fits slidably through the end of the handle 45 and is provided with a head 68. A finger-lever 69 is provided for opening the valve 66 and this lever is pivotally mounted for rocking movement as at 70 upon the upper side of the handle and has a finger-piece 71 projecting forwardly beyond its pivot and a finger 72 projecting rearwardly from the pivot and downwardly behind the end of the handle 110 and in engagement with the stem 67 and its head 68, as clearly shown in Figs. 1, 2 and 3 of the drawings. The valve 66 is normally held closed by means of a spring 73 which is fitted upon its stem 67 and bears at one end 115 against the valve and at its other end against one wall of the recess 63.

As before stated, a valve is provided for automatically controlling the supply of air under pressure to the motors and this valve 120

will now be described. The valve is positioned within the valve-chamber 74 which is formed in the handle 45 and which traverses the air passage 59. The valve includes a 5 piston which is slidably fitted within the valve-chamber 74 and comprises a head 75 and a head 76, these heads being connected by a stem 77, preferably integral with the head 76 and is threaded into the head 75, 10 the said heads being spaced with relation to each other. The chamber 74 is divided between the heads 75 and 76 of the piston, by a partition 78' held in place by means of pins 79 which project into sockets 80 formed 15 at opposite points in the wall of the chamber, these pins being projected into and held in engagement in the sockets by means of screws 81 threaded into the partition and having conical entering ends. The partition 20 78' is formed with ports 82 and the chamber 74 between the piston heads 75 and 76 is filled with oil or other fluid, as clearly shown in Fig. 1. A plug 83 is removably fitted into the upper end of the chamber 74 25 and a spring 84 is arranged within the chamber and bears at its upper end against the plug 83 and at its lower end against the piston head 75, this spring serving normally to lower the piston within the chamber, as 30 will be readily understood. In order that reciprocation of the head 75 in the chamber will not be interfered with by compression of the air above this head, vent openings 85 are formed in the plug 83. The lower end 35 of the chamber 74 is closed by means of a plug 86 and adjustably threaded through this plug is an abutment screw 87 held at adjustment by means of a jamb-nut 88. The upper end of the screw 87 is presented at the 40 axis of the head 76 and the spring 84 normally holds the valve lowered with its said head in engagement with the screw.

It will be observed from inspection of the drawings that by adjusting the screw 87 45 up or down, the valve may be normally so positioned as to more or less completely close the passage 59 so that when the throttle valve is opened by pressing upon the finger-piece of the throttle lever a greater or less volume of air will be admitted through 50 this passage.

As before pointed out, the pawls 14 may be positioned out of engagement in the notches 12 so as to permit of rotation of the 55 shaft 1 through the medium of the compressed air motors without however rotating the driving sprocket of the saw so that this shaft may be employed for the purpose of rotating an emery wheel or a chuck supported at its ends. The emery-wheel is indicated at 89 and includes a hub 90 fixed upon one projecting end of the shaft 1 and held thereon by means of a nut 91 threaded upon the said end of the shaft. One face 60 65 of the hub is formed with a ball-race 92

and seated in this race and in a similar race 93 formed in the face of the adjacent motor casing head 40 are bearing balls 94. The chuck above referred to is indicated by the numeral 95 and is fixed upon the opposite 70 end of the shaft 1 and carries a set-screw 96 which may be tightened to bear against and hold the tang of a bit 97 and fitted within the screw.

The operation of the device is as follows:—The governor shown in Fig. 1 of the drawings being in normal position, whereby to partly close the passage 59, the throttle valve is opened by depressing the finger-piece 71 of the throttle lever 69 thereby admitting air under pressure to the said passage. The air admitted is only in such volume as to set in motion the saw, or a tool supported by the shaft, but not sufficient to cause the saw or tool to cut through the 80 piece of material against which it is applied. However, as soon as the saw or the tool is applied to the material, the resistance offered to its movement will result in an increase in pressure within the valve-chamber 74, and as a consequence the piston valve within this chamber will be lifted. As the pressure within the motors overcomes the resistance offered to the travel of the saw, or rotation of the tool, the rotors 95 of the motors will be set in motion and the saw or tool will be caused to properly act upon the material. Should pressure within the motor casing become lowered, due to less resistance being offered to the rotation of the motor shaft the governor valve will 100 move downwardly a greater or less degree, but this movement will be comparatively slow, due to the fact that the fluid within the chamber 74 between the heads 75 and 76 105 must pass through the openings 82 in the partition 78', and it will be readily understood that when the valve has been lowered sufficiently to reduce the supply of air under pressure to the motors, sufficient to cause 110 an accumulation of air under pressure in the motor casings and the passage 59 and the chamber 74, the increased pressure will again result in a forward movement of the valve. By the provision of such a valve the 115 supply of air under pressure to the motors is governed in accordance with the character of the work being acted upon, and as a consequence, there is economical consumption of air and the motor shaft is not driven 120 at a high speed when it is unnecessary for it to be so driven.

Having thus described the invention what is claimed as new is:—

1. In a motor of the class described, a 125 casing, a rotor mounted in the casing, pistons carried by the rotor, the casing having an inlet port, one wall of the casing being formed with a number of exhaust openings and the rotor having a rim and the exhaust 130

openings in the wall of the casing being located within the boundary of the rim, and a by-pass in the said wall of the casing at the rim of the motor.

5 2. In a motor of the class described, a casing, a rotor mounted in the casing and having a peripheral rim extending between the heads of the casing, the said heads of the casing being provided with oppositely 10 located by-passes located at the rim of the rotor, the rotor being formed with passageways located inwardly of the rim, and an inlet for the casing, one head of the casing being formed with exhaust openings located 15 inwardly of the by-pass and within the boundary of the rim.

3. In a motor of the class described, a casing, a rotor mounted in the casing and having a hub and a peripheral rim extending 20 between the heads of the casing and supported upon the hub by a perforated web, the said hub of the casing being provided with oppositely located bypasses communicating at their ends with the space between 25 the said rim of the rotor and the curvilinear wall of the casing and the space within the rim, an inlet for the casing communicating with the space between the rim and the

curvilinear wall of the casing, pistons upon the rotor projecting into said space, one head 30 of the casing being formed with exhaust openings communicating with the space within the rim.

4. In a motor of the class described, a casing including sides and a rim, the casing having an inlet port opening through its rim, a rotor mounted within the casing, the rotor including a rim extending between the said sides of the casing, the said sides of the casing being outwardly bulged at a point 35 in the peripheral line of the rim of the rotor whereby to provide a by-pass between the space exteriorly of the rim of the rotor and interiorly of the same, and pistons carried by the rotor and projecting beyond the 40 rim of the same, the sides of the casing being provided with exhaust openings located within the boundaries of the rim of the rotor.

In testimony whereof I affix my signature 45 in presence of two witnesses.
